UNITED STATES PATENT OFFICE.

CHARLES T. WHITE, OF NEW YORK, N. Y.

DESIGN FOR A PACKING-CASE FOR PILLS.

Specification forming part of Design No. 7,433, dated May 12, 1874; application filed April 24, 1874.
[Term of Patent 7 years.]

To all whom it may concern:

Be it known that I, CHARLES T. WHITE, of the city, county, and State of New York, have invented a new and original Design for Packing-Cases, of which the following is a specification:

The nature of my design is fully represented in the accompanying photographic illustration, to which reference is made.

This design represents a knapsack, *a*, having a rolled-up blanket, *b*, strapped to its top part. *c c* are the straps. In the center of the knapsack is a white ground, *d*, having thereon the capital letter K. Above this white ground, in white Roman capitals and on a black ground, is the word "Knapsack." I prefer to make the knapsack of black color, and with black straps and blanket, but any other color may be used.

This design is intended for a pocket-package of pills or other medicine, and is usually made of paper, and may be ornamented in any manner to suit the taste.

The distinctive feature of the design is the figure of a knapsack, bearing the word "knapsack" on the back and the letter K in the center.

I claim as my invention—

The design for a pill or medicine box, consisting of a figure of a knapsack with the word "knapsack" and letter K on the back, as shown.

CHARLES T. WHITE.
